UNITED STATES PATENT OFFICE

2,566,296

TOY FOR BLOWING SMOKE-FILLED
BUBBLES

Mary A. Brosseit, Chicago, Ill.

Application August 1, 1946, Serial No. 687,761

2 Claims. (Cl. 46—8)

1

My invention relates to devices or toys used for producing bubbles, and more particularly to those devices which are simulative or symbolical of popular objects, and one object of the present invention is to provide a toy which simulates a jet-propelled airplane.

A further object is to provide a toy of the above character which employs the element of smoke as a medium for filling the bubble made by the toy or to escape from the same in simulation of a fuel jet.

Another object is to design the novel toy with a solid portion constructed for the formation of the bubble and a pliable portion for securing the necessary air pressure to form the bubble.

An additional object is to construct the toy along lines of simplicity and ruggedness, so that it may be economically produced, roughly handled without damage and operated efficiently over an extended period.

With the above objects in view, and any others which may suggest themselves from the description to follow, a better understanding of the invention may be had by reference to the accompanying drawing, in which—

Fig. 1 is a longitudinal section of the device, and

Fig. 2 is a section on the line 2—2 of Fig. 1.

In accordance with the foregoing, specific reference to the drawing indicates the device to be generally in the form of an airship having a body 10, a nose 11, and wings 12. It is understood that, while the drawing shows a given form for the device, various modifications of such form may be employed.

The body 10 is made of rubber or other pliable material, and is hollow on the inside, while the nose 11 is made of hard material and with a reduced and threaded portion 13 at the rear, upon which the open front end of the body 10 may be screwed. With the body made of fairly thick rubber—as indicated—it is evident that a firm threaded connection between the same and the nose 11 is feasible.

The nose 11 forms a frontal compartment 14, and the bottom of the latter is vertically bored at 15 and also tapped at 16 to receive a tube 17. The upper portion of the tube rises into the compartment 14 and terminates rearwardly with a curved portion 18. The tube 17 also has an aperture 19 made in its side wall in the region of the floor of the compartment 14. Below this zone, the tube is enlarged and threaded into the tapped portion 16, having a collar 20 below the threaded

portion as a stop. The tube continues in downward direction as indicated at 21.

It is intended that the lower end of the tube 15 give off a saponaceous solution effective to form a bubble 25, the solution being indicated at 26. The aperture 19 allows a very small amount of the solution to enter the tube; and air pressure into the mouth 18 of the tube 15 will cause the solution to expand in the usual manner and form a bubble.

The body 10 of the device forms a bulb which may be squeezed to supply air pressure into the compartment 14. For this purpose the rear wall 13 of the compartment forms a partition between the same and the body 10 and also a support for a horizontal tube 27 by way of which the air pressure is transmitted. Thus, it is only necessary to squeeze the body 10 at any time when the formation of one or more bubbles is desired.

Another feature of the invention is the introduction of smoke into the air contributing to the formation of the bubble. This is done by forming the partition 13 with a receptacle 28 extending into the body 10 and receiving a stick 29 of incense, such stick being longitudinally bored at 30 or made sufficiently porous to permit smoke therefrom—when the incense is burning—to be forced forwardly into the tube 27 and chamber 14, so that the smoke is transmitted with the air entering the tube 15.

It will be apparent from Fig. 1 that the tube 15 may be rotated to raise or lower the aperture 19 in relation to the floor of the compartment 14. This varies the size of the passage in the aperture and therefore controls the amount of liquid 35 which may enter the tube 15. Also, when the tube is unscrewed one or two turns the aperture enters the stock of the compartment bottom and creates a shut-off for the liquid in the compartment, so that the device may be put in the pocket, in a drawer, or in any other place when it is not to be used, without the chance of leakage.

It is also noted that the body 10 has an outlet tube 30 in the bottom, such tube having a rearward extension 31. When a sufficient amount 45 of smoke develops in the body 10, the squeezing thereof will create puffs of smoke issuing from the tube 31 in a rearward direction, such puffs simulating those of a jet-propelled airplane. When this feature is not to be used, a closing cap 50 32 is applied to the rear end of the tube 31.

It will now be apparent that I have provided a toy which is fascinating from its modern aspect as well as exceedingly interesting in its use. In other words, a toy is provided which not only

looks like an airplane or airship, but has the added facility of creating bubbles. It is understood that the compartment 14 may be filled with the bubble liquid by simply dipping the lower portion 20 of the tube 15 into a cup containing the saponaceous solution while the body 10 is compressed, and allowing the body to expand to its normal size. Further, the size of the bubbles may be controlled by turning the tube 15 slightly in one or the other direction, while the tube also forms a complete shutoff when desired, as previously explained. Further, the smoke-jet feature is easily obtainable by lighting the incense and allowing smoke to fill the body 10. Further, the projection of the tube 27 from the back of the compartment 14 prevents the passage of the solution 26 into the body 10 of the device in case the latter is tilted back to an inclined or vertical position. Finally, it will be apparent that the construction of the device is quite simple, and that it may be produced economically and handled or used with facility after one or two trials.

While I have described the invention along specific lines, various minor changes or refinements may be made therein without departing from its principle, and I reserve the right to such changes or refinements as may come within the scope and spirit of the appended claims.

I claim:

1. A toy simulative of an airship body with one end portion of firm material formed as a compartment and divided by a partition from the balance of said body, such balance being a pliable bulb and the bottom of the compartment serving to hold a quantity of bubble-making liquid, a tube rising through said bottom into the compartment space above said liquid and having a side inlet for the liquid at a point above said bottom, a second tube extended from the bulb through said partition into the compartment for the transmission of air thereinto when the bulb is compressed, such air influencing the entrance of a portion of said liquid into the first tube by way of said inlet to issue from the lower end of such first tube in bubble form, and the extension of the second tube into the compartment being sufficient to place its free end above the level of said liquid in case the body is tilted

from a normally horizontal position to locate said partition as the bottom of the compartment, said partition being extended with a receptacle on the side opposite from said second tube, the receptacle communicating with the latter and adapted to receive an incense element.

2. A toy simulative of an airship body with one end portion of firm material formed as a compartment and divided by a partition from the balance of said body, such balance being a pliable bulb and the bottom of the compartment serving to hold a quantity of bubble-making liquid, a tube rising through said bottom into the compartment space above said liquid and having a side inlet for the liquid at a point above said bottom, a second tube extended from the bulb through said partition into the compartment for the transmission of air thereinto when the bulb is compressed, such air influencing the entrance of a portion of said liquid into the first tube by way of said inlet to issue from the lower end of such first tube in bubble form, and the extension of the second tube into the compartment being sufficient to place its free end above the level of said liquid in case the body is tilted from a normally horizontal position to locate said partition as the bottom of the compartment, said partition being extended with a receptacle on the side opposite from said second tube, the receptacle communicating with the latter and adapted to receive an incense element, an outlet conduit from the bulb, and a removable closure for such outlet.

MARY A. BROSSEIT.
